F. W. Parker

UNITED STATES PATENT OFFICE.

JAMES E. SIMPSON, OF BROOKLYN, NEW YORK.

LINE-FORMING DEVICE FOR TYPE-WRITING MACHINES.

1,225,369.

Specification of Letters Patent.

Patented May 8, 1917.

Application filed May 1, 1916, Serial No. 94,526. Renewed January 16, 1917. Serial No. 142,742.

To all whom it may concern:

Be it known that I, JAMES E. SIMPSON, a citizen of the United States, and resident of the borough of Brooklyn, in the county of Kings and State of New York, have invented certain new and useful Improvements in Line-Forming Devices for Type-Writing Machines, of which the following is a specification.

10 This invention relates to line forming devices for type-writing machines, and it has particular reference to means, attachable to machines of various makes, or forming a permanent part of the equipment thereof, whereby in the movement of the paper carriage longitudinal lines may be drawn, and in the revolving movement of the platen vertical lines may be drawn.

My improvements further contemplate, 20 for the line producing medium, the employment of a self-inking wheel, or roller having a narrow periphery, which is supported near the platen, to normally not interfere with the operation of the types; but to be 25 movable into direct contact with the paper on the platen as occasion requires. Said self-inking roller or the like is adjustable into both horizontal and vertical positions, that it may be capable of drawing or ruling 30 either horizontal or vertical lines, and it is provided with detaining means, for holding it in either one of those set positions.

With these and other objects in view, my invention consists of a holder, capable of 35 attachment to a type-writing machine, and having a line forming wheel pivoted therein. The arrangement is such that the peripheral edge of said wheel, which is narrow, to produce a line of suitable width, is 40 in opposed relation to the platen, near the printing point thereon, but spaced therefrom. Within said holder, at the rear of and in tensional contact with said wheel, is an inking pad which may be in the form 45 of a roller, to supply ink to said wheel in the rotation of the latter. Said inking pad may be removably supported in said holder, for purposes of replacement.

The holder may be loosely supported in 50 a suitable bearing, to be capable of reciprocating movement, to and from the platen, and to enable the line forming wheel to move into either a horizontal or vertical position. The wheel may be held normally 55 inactive, as by a spring to retract the holder, and detaining means, as a spring, may be

provided to hold the wheel in a set position for producing either a horizontal line, or a vertical line.

Other features and advantages of my said 60 invention will hereinafter appear.

In the drawing:

Figure 1 is a side elevation, enlarged, of my improved device, shown in conjunction with portions of a type-writing machine, 65 and

Fig. 2 is a top plan view thereof, and Fig. 3 is a similar view of a modification.

Parts only of a type-writing machine, broken away, are shown in the views, including the frame 1, platen 2, and a type bar 3, these portions however serving to illustrate the relative arrangement, with a type-writing machine, of my line forming device. Thus, a bracket 4 is here shown as 70 attached to the front plate (for convenience) of a "Royal" machine, said bracket comprising a bearing 5, in which a rod 6 is mounted to both revolve and reciprocate, an extending portion of said rod, at one 75 side, having a push button 7, and an extending portion at the other side, as 8, having squared surfaces 9. Between the bearing 5 and push button 7 there may be a spring 10, to hold the rod normally extended at 80 that side; and means, as a flat spring 11, secured at one end to the bracket, may bear upon one of the squared surfaces 9, to tensionally stay the rod 6 in a set rotated position, for a purpose to be described herein- 85 after. Mounted upon the squared portion 9 is a holder for the line forming device. This holder may consist of an angle plate 90 comprising the end portion 12 which is connected to the rod 6, and the side portion 95 13 which projects in the direction of the platen. Said portion 13, at its free end, may have a web 14, which carries a plate 15 that is parallel with portion 13, and, with said plate 13, provides bearings for a shaft 100 16, carrying wheel 17. Secured within the aforesaid holder, as to end portion 12, is a spring 18, which is provided, at its free end, with a pin 19, lying transversely of the holder to form a pivotal bearing of an ink 105 roller 20, which is mounted thereon, at the rear of wheel 17, and is pressed by said spring into ink imparting contact with said wheel. A plate 21 may be hinged to the holder portion 12, as at 22, that it may 110 close, as a gate, into the position shown in dotted lines in Fig. 2, where it is in parallel-

ism with holder portion 13, and may provide a bearing for the end of pin 19; or said plate 21 may swing open to the position shown in full lines in Fig. 2, thereby permitting the ink roller 20 to be freely removed from pin 19 and the holder, and a new one put in its place.

The wheel 17 may be of suitable construction, but is characterized by having a narrow peripheral edge, of desirable contact contour and width, whereby it may receive ink from the ink roller 20, and, in rolling over the paper, as the platen or paper support is moved to and fro—or revolved—thereby impress upon the paper a clear and sharp ink line of any length.

In the drawing the holder is shown in such rotated position that the wheel 17 is presented vertically with relation to the platen, so that, upon applying inward pressure to the push button 7, to press the wheel against the platen, and then by revolving the platen, a vertical line will be drawn upon the paper carried by the platen. If, instead, a horizontal line is to be drawn, then the holder is given a quarter turn in its bearing 5, the spring 11 yielding in that act until it comes to rest upon the squared face 9 which represents the other position for the wheel—that in which the wheel is disposed horizontally, to draw a horizontal line. Then, upon applying the same pressure through push button 7, and moving the platen laterally, a horizontal line will thereby be produced.

Means, such as herein shown, may be employed for producing lines of different colors, as for example by the use of two line producing wheels, each having a separate ink roller of different colors, both pairs of wheel and roller being carried by the same holder, and capable of alternating in their operative relation with the platen.

In Fig. 3 I have shown a holder 23, in which are independently mounted the ink marking wheels 24 and 25, for different colored inks; the wheel 24 having a fixed bearing in said holder, and deriving its ink feed from a roller 26, which is supported in the holder in a fixed position relatively to said wheel 24; whereby said marking wheel 24 is operable, with the holder 23, in the same manner as the device shown in Figs. 1 and 2.

The holder 23, as stated, may also carry a second marking wheel 25, mounted as on an adjustable strip 27, which is slidable in guides 28; said strip 27 having a detent 29, adapted to enter a recess or seat 30 in the holder; although, in the drawing the recess or seat is shown as formed upon a spring piece carried by said holder; the purpose of said seat or recess being to retain the strip 27 in a projected position in which the wheel 25 is held in operative contact with the platen, or with a work sheet there-

on. The strip 27 also carries an ink feed roller 31, for the wheel 25, and in operative relation therewith; whereby, when said strip 27 is projected to adjust the wheel 24 beyond the position of the wheel 24, said wheel 24 may thereby be brought into pressure contacting relation with the platen, to mark the work sheet in the movement of the platen against said pressure.

Variations may be resorted to within the spirit and scope of my said invention, and parts thereof used without others.

I claim:

1. The combination, in a typewriting machine, having a revoluble platen, with endwise movement, of a pair of line forming wheels, having inking means of different colors respectively, a holder therefor, means for slidably supporting said holder for movement toward and from said platen, means for shifting one of said wheels in advance and rearwardly of the other wheel, and means for detaining said shiftable wheel in its set positions.

2. In a typewriting machine, the combination of a revoluble platen having an endwise movement, a line forming wheel having inking means, a slidably and rotatably mounted support for said wheel whereby said wheel may be reciprocated toward and from the platen with the axis of the wheel parallel with or at right angles to the axis of the platen, and yieldable means engaging said support to slidably hold the support in its rotatably adjusted position.

3. A line forming device, comprising a line forming wheel having inking means, a holder for said wheel, means for slidably supporting said holder for movement toward and from a platen, means for rotating said holder to position the wheel to form lines of various angles, yieldable means having a sliding engagement with said holder to maintain the wheel in its set position, and yieldable means for normally retracting the slidably holder from the platen.

4. A line forming device, comprising a line forming wheel having inking means, a rotatably mounted holder for said wheel, means for moving said holder toward and from a platen and for rotating said holder to set the wheel to form lines of various angles, bearing surfaces on said holder, and a spring adapted to slidably and yieldably engage either of said bearing surfaces to maintain the wheel in set position and permit reciprocation of the holder.

5. In a typewriting machine, the combination of a frame, a rotatable platen having an endwise movement, a line forming wheel, a holder for the wheel, means for slidably supporting the holder for movement toward and from the platen, bearing surfaces on the holder, means mounted on a stationary part of the frame adapted to

- slidably and yieldably engage either of said bearing surfaces to maintain the wheel in set position, and means for rotating said holder against the resistance of said yieldable means to set the wheel.
6. In a typewriting machine, the combination of a frame, a rotatable platen having an endwise movement, a line forming wheel, a holder for the wheel, means for 10 slidably supporting the holder for movement toward and from the platen, bearing surfaces on the holder, means mounted on a stationary part of the frame adapted to slidably and yieldably engage either of said bearing surfaces to maintain the wheel in set position, means for rotating said holder against the resistance of said yieldable means to set the wheel, and means for normally retracting the slidable holder from 15 the platen.
7. In a typewriting machine, the combination of a frame, a rotatable platen having an endwise movement, a plurality of line forming wheels, an independent inking means 20 for each wheel, a holder for the wheels, means for slidably supporting said holder for movement toward and from the platen, means for rotating the holder to set the wheels for presentation to the platen to 25
- form lines of various angles, relatively fixed 30 means carried by the frame adapted to maintain the holder in its adjusted position and permit reciprocation of the holder in its set position toward and from the platen, and means for varying the relative positions of 35 the wheels in the holder whereby either of said wheels may be rendered inoperative.
8. In a typewriting machine, the combination of a frame, a platen, a bracket rigidly mounted on the frame, a line-forming wheel, 40 a holder for said wheel slidably mounted in said bracket for moving the wheel toward and from the platen, means for rotating said holder to position the wheel to form lines 45 of various angles, means for maintaining the holder in its rotatably adjusted position, said means permitting reciprocation of the holder to move the wheel to and from line-forming position, and means for normally 50 retracting the holder from the platen.

Signed in the borough of Brooklyn in the county of Kings and State of New York this seventh day of February A. D. 1916.

JAMES E. SIMPSON.
